UNITED STATES PATENT OFFICE.

WALTER B. SCOTT, OF MARBLEHEAD, MASSACHUSETTS.

TOY CONSTRUCTION.

Application filed February 26, 1921. Serial No. 442,213.

To all whom it may concern:

Be it known that I, WALTER B. SCOTT, a citizen of the United States, residing at Marblehead, in the county of Essex and State of Massachusetts, have invented an Improvement in Toy Construction, of which the following is a specification.

This invention has particular reference to the manufacture of toys, although not limited to toys alone, wherein a relatively thin member, as a plate and disc, is to be secured, either firmly or rotatably, to a small rod or shaft, and a shaft rotatably supported in a non-metal supporting member; and various non-metal members are to be secured to metal members, and the like.

In securing a thin wooden wheel to a small metal shaft, for instance, much difficulty has been experienced in uniting both in such a manner that the wheel will run true and will not become loose; and to obtain these results in an inexpensive manner.

An object of this invention is to provide a novel and inexpensive means to connect the members above enumerated with each other and, specifically, to connect a non-metallic member to a metallic member.

A further object is generally to improve the construction of toys and the like.

This application is a continuation in part of my co-pending application Serial No. 374,799, filed April 19, 1920, patented under date of November 8, 1921 and Number 1,396,289.

Fig. 1 is a detail of a toy construction illustrating the method of firmly securing a thin wooden wheel to the end of a small driving shaft, and rotatably supporting the shaft in a narrow supporting member.

Fig. 2 is a detail illustrating a shaft having a wheel fixed to its middle portion and thin metallic members, specifically cranks, fixed to its ends.

Fig. 3 is an end view of a crank of Fig. 2. Fig. 4 is a detail illustrating a crank-shaft rotatably supported in metal bearing members.

Fig. 5 is a detail illustrating the method of pivotally connecting two relatively movable non-metal members.

Fig. 6 is a detail illustrating two spaced wooden members connected by a metal rod.

Fig. 7 is a detail illustrating the method of providing a shaft or rod with end-flanges.

Fig. 8 is a detail illustrating a thin metal disc or wheel fixed to the end of a metal

shaft and the shaft rotatably supported in a fixed, non-metal supporting member.

Figs. 9 and 10 represent constructions wherein the shaft-receiving aperture in the wheel is out of perpendicular and illustrate the manner of securing the shaft therein perpendicularly to the wheel.

The various figures of the drawings represent various constructions embodying the invention. Fig. 1, for instance, illustrates the invention embodied in the means for securing the wooden wheel 10 to the metal axle or shaft 11. It has heretofore been difficult to secure the thin wheel to the shaft in such a manner that it would run true and would not become loose thereon, inasmuch as the wheel has a tendency to shrink and swell in accordance with variations in atmospheric conditions. In carrying out the invention in this particular construction, the wheel is formed with an aperture therethrough and a metal tubular member 12, as an eyelet, having an outwardly-extended flange 13 is passed through the aperture. The relative dimensions of the tubular member and the aperture are such that, preferably, said member is a force fit therein, although this is not essential. The end of said member is adapted to extend on one side beyond the body of the wheel and the extended end is upset to form the outwardly-extended flange 14. Both flanges of the tubular member are compressed toward each other and against and into the body of the wheel and thereby firmly to engage it; and the width of the flanges is adapted to be such that sufficient frictional engagement is obtained to provide a permanently fixed union. The shaft 11 is extended into the tubular member until its end is about flush with the flange 13 and is firmly secured to the member as by solder 15; and is thereby firmly fixed to the wheel. The solder may be built upon the flange 13 to form the ornamental head shown and also impart additional strength to the union between the shaft and wheel. Preferably the diameter of the shaft 11 is such that it will snugly fit within the tubular member but some clearance is desirable in order to permit the solder to run between and firmly unite both.

It is not essential that the aperture in the wheel be precisely perpendicular to the wheel in order to secure the shaft perpendicularly thereto. In Fig. 9 the aperture is represented as inclined from the perpen-

dicular. The eyelet 12 in this case is smaller than the aperture and is secured therein with its axis perpendicular to the wheel. In Fig. 10 the eyelet 12 is inclined from the perpendicular and the shaft 11 is sufficiently smaller than the bore of the eyelet to permit it to be perpendicularly arranged and soldered to the eyelet. In both constructions the shaft is as firmly secured to the wheel as in the construction illustrated in Fig. 1.

In Fig. 2 the wheel 10^a is disposed on the middle of the shaft 11^a and securely fixed thereto by the solder 15, as before.

The metal disc or wheel 17 may be secured 15 to the shaft 11^b, see Fig. 8, by forcing the flanges of the eyelet 12^b into firm engagement with the opposite faces of the wheel and soldering the shaft in the eyelet.

Fig. 2 also represents the manner of securing the thin wire or rod member 18 to 20 the shaft 11^a. Said wire member is formed with the eye 18^a and the eyelet 19 is inserted through the eye and its flanges 20 and 21 compressed against the body of the member. 25 The shaft 11^a is then inserted in the eyelet and solder run into the interstices between the shaft and eyelet and between the eyelet and said member 18 thereby firmly uniting all members together.

30 A somewhat similar construction is employed to provide a bearing for the shaft 11 of Fig. 1. The supporting or frame member 22 is of wire or rod of small diameter and its end portion is reflexed to form an eye 22^a. An eyelet 19^a is inserted through said eye and its flanges 20^a and 21^a are compressed against the frame member and firmly engage it. If found desirable, the eyelet may be soldered in the eye 19^a which provides a bearing having but little friction.

Fig. 4 illustrates more particularly a construction wherein the shaft 25 is provided with eyelets 26 and 27 fixed thereto and which are rotatable in the eyelets 28 and 29 which latter are secured by soldering to the frame members 30. It will be noted that, in this case, the eyelets have only the single flanges 26^a and 27^a which engage the fixed eyelets 28 and 29 and retain the shaft 25 50 against axial displacement.

A somewhat similar construction is illustrated in Fig. 6, wherein the wooden members 31 and 32 have the eyelets 26^a and 27^a preferably frictionally received in apertures 55 therein with their heads 26^b and 27^b on the outside of said members. The rod 25^a is extended through the eyelets and soldered to both, thereby to prevent said members from outward movement.

60 In Fig. 5 the two relatively movable wooden members 35 and 36 have the eyelets 37 and 38 therein which form bearing members; and said wooden members are pivotally connected by the metal rod 39 having the

eyelets 40 and 41 soldered thereto. Said eyelets form complementary bearing members with the eyelets 37 and 38 of said wooden members 35 and 36 and the flanges 40^a and 41^a of said eyelets 40 and 41 serve to retain said wooden members in place on said rod. 65 70

In Fig. 7 the metal rod 45 is provided with flanged ends by applying the eyelets 46 and 47 over the ends thereof and soldering them to the rod with the flanges 46^a and 47^a outermost. The arrangement of the rod 75 and eyelets is similar to that shown in Fig. 6.

Fig. 8 also illustrates a wooden supporting member 50 having an aperture therethrough and an eyelet 51 in the aperture with the flanges 51^a and 51^b frictionally engaging opposite sides of said member and forming a bearing member adapted rotatably to support said shaft 16^b extended therethrough.

While I have herein described the non-metallic member as of wood, yet said member may be of other non-metallic material, as paper, fibre, celluloid and the like; and whereas I have described two members as being "soldered" together, I intend also to include other securing means as, a brazing metal, rosin, an adhesive and the like; and I may conceivably weld the two members together.

The invention may also be embodied in 95 constructions other than those herein illustrated and described without departing from the spirit thereof.

I claim:

1. The combination of a wooden disc having an aperture therethrough, a metallic tubular member having an outwardly extended flange at one end received in said aperture and having an end-portion extended therethrough, and said end-portion upset to 100 form a second outwardly extended flange, said two flanges embedded in the opposite faces of said disc and firmly engaging it, and a metallic shaft inserted in said tubular member and soldered thereto, by which said 105 wooden disc and metal shaft are firmly united.

2. The combination of a non-metallic member having an aperture therethrough, a metallic tubular member having an outwardly-extended flange at one end received in said aperture and having an end-portion extended therethrough, and said end-portion upset to form a second outwardly-extended flange, said two flanges compressed into firm 115 frictional engagement with said non-metallic member, and a metallic shaft inserted in and attached to said metallic tubular member, whereby said shaft and non-metallic member are rigidly united.

In testimony whereof, I have signed my name to this specification.

WALTER B. SCOTT.
